UNITED STATES PATENT OFFICE.

GEO. E. KING, OF NEW YORK, N. Y.

IMPROVEMENT IN FLUTED PUFFING FOR SHIRT-BOSOMS.

Specification forming part of Letters Patent No. **59,036**, dated October 23, 1866.

To all whom it may concern:

Be it known that I, G. E. KING, of the city, county, and State of New York, have discovered or invented a new and useful Fluted Puffing applicable to Shirt-Bosoms and other parts and articles of dress, the same constituting a new article of manufacture; and I do hereby declare that the following is a full, clear, and exact description of the same, reference being had to the accompanying drawings, which form part of this specification, and in which—

Figure 1 represents a face view of a section of my new fluted puffing previously to its being washed; Fig. 2, an outside edge view of the same; Fig. 3, a sectional edge view thereof; and Fig. 4, a front or face view of the puffing after having been washed, and as sewed between the plaits of a shirt-bosom.

Similar letters of reference indicate corresponding parts throughout the several figures.

Without confining myself to any precise mechanism for manufacturing my fluted puffing, I would here observe that to produce it machinery is necessary not only as regards its fluted surface, but also its flattened borders, and the article being completed by machine-stitching.

The following description will suffice to explain how this may be done: I take a strip of muslin of any desired length and width, and run it, for instance, through or between a pair of heated rollers formed with flutes on their peripheries, the flutes of the one roller meshing into the flutes of the other, and both rollers provided with flat-edged flanges on either side of them, working in such close proximity—that is, the flanges of the one roller with the flanges of the other—as, in running the strip of muslin between the fluted and flanged surfaces or peripheries of the rollers, it will

issue from them with a central fluted surface, A, for a greater portion of its width throughout the length of the strip, but with a hard-pressed flattened border, B, on or along each opposite edge or edges of it on both sides or faces of the strip. I then take this fluted strip, with its flattened borders, and run it successively, for each edge or border B, under or through a sewing-machine, and so that a thread or line of stitching, a, will be run along either border at the extremities of the flutes, thereby tacking or binding the flutes in a regular and systematic manner, and at the same time binding or tacking the borders B, which, being formed by the flanges of the rollers compressing or flattening down the extremities of the flutes, will be, as it were, of double thickness and desirable strength, without a separating-binding for stitching them to or between the plaits b of a shirt-bosom, or otherwise attaching them to other parts or articles of dress.

Thus may a puffing of the greatest regularity and strength be produced at a trifling cost and with great celerity.

What I claim is—

The within-described fluted puffing, as a new article of manufacture, and made by fluting by mechanism, and in a regular manner, a strip of muslin or other material throughout its length, and compressing and flattening down the extremities of the flutes to form straight and regular borders on either and opposite sides of the flutes, and afterward machine-stitching said borders along and at the union of the borders with the flutes, substantially as specified.

GEO. EDWIN KING.
